CLAIM

The ornamental design for a blender, as shown and described.

DESCRIPTION

FIG. 1 is a front perspective view of a blender; FIG. 2 is a rear perspective view of the design shown in FIG. 1; FIG. 3 is a front elevation view of the design shown in FIG. 1; FIG. 4 is a right side view of the design shown in FIG. 1; FIG. 5 is a rear elevation view of the design shown in FIG. 1; FIG. 6 is a left side view of the design shown in FIG. 1; FIG. 7 is a top plan view of the design shown in FIG. 1; and, FIG. 8 is a bottom plan view of the design shown in FIG. 1. The broken line and the area within it in FIG. 8 depict portions of the blender that form no part of the claimed design.

1 Claim, 8 Drawing Sheets
